UNITED STATES PATENT OFFICE.

ANDREW S. FISHER, OF ALTOONA, PENNSYLVANIA.

WRENCH.

Application filed June 22, 1920. Serial No. 390,694.

To all whom it may concern:

Be it known that I, ANDREW S. FISHER, citizen of the United States, residing at Altoona, in the county of Blair and State of Pennsylvania, have invented certain new and useful Improvements in Wrenches, of which the following is a specification.

This invention relates to an improved wrench and has as one of its principal objects to provide a wrench of the flat type which may be readily adjusted.

The invention has as a further object to provide a wrench employing companion jaw members providing a pair of coacting jaws at each end of the wrench and wherein the maximum span of one pair of jaws will substantially conform to the minimum span of the other pair of jaws so that a practically continuous range of adjustment will be had up to the maximum span of the largest pair of jaws.

And the invention has as a still further object to provide a wrench wherein the jaw members will be slidably connected by an adjusting element therefor and wherein the pair of jaws at either end of the wrench may be moved toward each other and forcibly urged into engagement with a nut by simply shifting said member forwardly toward the end of the wrench engaged with the work.

Other and incidental objects will appear hereinafter.

In the drawings:

Figure 1 is a front perspective view of my improved wrench,

Figure 2 is an edge elevation of the device,

Figure 3 is a rear elevation of the wrench,

Figure 4 is a perspective view showing the adjusting element of the wrench in detail, and

Figure 5 is a fragmentary plan view showing the manner in which the wedge shaped studs of the adjusting element are adapted to coact with the walls of the slots of the jaw members.

In carrying the invention into effect, I employ companion jaw members 10 and 11 respectively. These jaw members are in the nature of flat plates and are formed at their ends with slightly offset jaws, the jaws at corresponding ends of the plates mating so that a pair of jaws 12 is provided at one end of the wrench and a pair of jaws 13 at the opposite end of the wrench. As will be observed, the parallel working faces of the

jaws 12 are directed obliquely in one direction with respect to the longitudinal axis of the wrench while the parallel working faces of the jaws 13 are directed obliquely in the opposite direction, one pair of jaws being shown in the present instance as formed to receive a hexagonal nut while the other pair is shown as formed to receive a square nut. As will be once appreciated, this structural detail may be varied as desired, it being contemplated that the jaws may, within the spirit of the invention, be variously formed, as, for instance, to provide an alligator wrench. At their outer ends, the jaws of the member 10 are formed with raised thickened portions 14 lying flush with the upper faces of the jaws of the member 11 while at the outer ends of the jaws of this latter member are formed depending thickened portions 15 lying flush with the lower faces of the jaws of the member 10. As particularly shown in Figures 1 and 3 of the drawings, the thickened portions are formed at their inner transverse edges with oblique undercut shoulders 16 while at the bases of the jaws the jaw members are formed with beveled shoulders mating with the first shoulders. As will be appreciated, these shoulders will tend to prevent separation of the jaws at right angles to the plane thereof. Formed in the jaw member 10 near opposite ends thereof is a pair of obliquely directed slots 17 and formed in the jaw member 11 is a pair of similar slots 18 inclining in a direction opposite to and intersecting the first slots.

Slidably connecting the jaw members is an adjusting element 19 therefor. This adjusting element comprises a body plate which, as shown in Figures 1 and 2, rests flat against the jaw member 11 at the upper side of the wrench and is medially provided with laterally directed lugs or ears 20 which, as best shown in Figure 3, overhang the jaw members. Upstanding from the plate near its ends are oppositely directed wedge shaped studs 21 which are freely received through the intersecting slots 17 and 18 of the jaw members and threaded upon the upper ends of said studs are nuts 22 slidably connecting the jaw members with each other as well as also slidably connecting the adjusting element with said members.

Attention is now directed to the fact, as particularly brought out in Figure 5, that

the sloping faces of the studs 21 will coact with the converging walls of the slots of the jaw members for sliding these members one upon the other when the adjusting element 5 is shifted longitudinally of the jaw members. Consequently, in the practical use of the tool, either pair of jaws thereof may be moved into binding engagement with a nut by simply shifting the adjusting element 10 forwardly toward the pair of jaws so engaged with the nut. As will be clear, by increasing the forward thrust upon the adjusting element the binding action of the jaws against the nut will be increased proportionately so that the jaws may be caused 15 to securely grip the nut and thus obviate slipping. Due to the wedge shape of the studs, an elongated bearing area is provided between said studs and the walls of the slots 20 17 and 18 so that mutilation of said walls will be obviated while, at the same time, extreme wedging force tending to move the jaw members inwardly upon each other may be brought to bear upon said members. As 25 will be perceived, closing of the jaws 12 will serve to open the jaws 13 and vice versa closing of the jaws 13 will serve to open the jaws 12. The jaws 13 are somewhat larger than the jaws 12, the jaws 12 being 30 designed, of course, for light work while the jaws 13 are intended for heavy work. Preferably, the wrench is so constructed that the maximum span of the jaws 12 is, as shown in Figure 3, substantially equal to the minimum span of the jaws 13. By this arrangement a continuous range of adjustment is had from the minimum span of the jaws 12 up to the maximum span of the other pair 35 of jaws. I accordingly provide a highly 40 efficient wrench structure and a wrench which will be found particularly serviceable in practical use.

Having thus described the invention, what is claimed as new is:

- 45 1. A wrench including companion jaw members having coacting jaws, and an adjusting element at the outer side of one of the members slidably connecting said members, the adjusting element being movable longitudinally of the members for shifting 50 the members transversely and moving the jaws relative to each other.
2. A wrench including companion jaw members lying one against the other and 55 having coacting jaws, the members being provided with integral transversely directed coacting means securing the members against

separation at right angles to the jaws, and an adjusting element at the outer side of one of the members slidably connecting the members and movable longitudinally thereof for shifting the members transversely and moving the jaws relative to each other. 60

3. A wrench including companion jaw members having coacting jaws, one of the jaws being formed with a thickened portion having a shoulder and the other of the jaws having a shoulder at its base coacting with the first shoulder for securing the jaws against separation at right angles to the plane thereof, and an adjusting element at the outer side of one of the members slidably connecting the members and movable longitudinally thereof for shifting the members transversely and moving the jaws relative to each other. 70

4. A wrench including companion jaw members having coacting jaws, and a longitudinally extending adjusting element at the outer side of one of the members slidably connecting the members and movable longitudinally thereof for shifting the members transversely and moving the jaws relative to each other, said element having means overhanging the side edges of one of said members whereby when manipulating the wrench said means may be grasped for shifting the jaws. 80

5. A wrench including companion jaw members having coacting jaws and provided with intersecting oblique slots, and an adjusting element slidably connecting the members and having wedge shaped studs projecting through said slots, said studs having flat sides forming inclined flat bearing surfaces coacting with the oblique walls of said slots whereby said element may be shifted longitudinally of the members for moving the jaws relative to each other. 90

6. A wrench including companion jaw members having coacting jaws, and a longitudinally extending adjusting element at the outer side of one of the members slidably connecting the members and movable longitudinally thereof for shifting the members transversely and moving the jaws relative to each other, said element having ears overhanging the side edges of one of said members at a point between the ends thereof whereby when manipulating the wrench said ears may be grasped for shifting the jaws. 100

In testimony whereof I affix my signature.

ANDREW S. FISHER. [L.S.]
